PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DRAFT AND CENTER SILL CONNECTION.

1,109,610

Specification of Letters Patent.

Patented Sept. 1, 1914.

Application filed March 9, 1914. Serial No. 823,390.

To all whom it may concern:

Be it known that I, PAUL M. BEARD, a citizen of the United States, residing at the city of St. Louis, State of Missouri, have invented a certain new and useful Improvement in Draft and Center Sill Connections, of which the following is a full, clear, and exact description, such as will enable others skilled in the art to which it appertains to make and use the same, reference being had to the accompanying drawings, forming part of this specification, in which—

Figure 1 is a top view of a fragmentary portion of a car underframe embodying my invention. Fig. 2 is a side view partly in section taken on line 2—2 of Fig. 1, and illustrating the connection of the center sill with the bolster and a draft sill. Fig. 3 is a view in section on line 3—3 of Fig. 1. Fig. 4 is a detail showing a top view of the connector plates in position. Fig. 5 is a detail showing an outside view of one of the connector plates in elevation. Fig. 6 is a detail showing an inside view of a connector plate in elevation. Fig. 7 is a view taken on line 7—7 of Fig. 5. Fig. 8 is a sectional view on line 8—8 of Fig. 5. Fig. 9 is a detail taken in section on line 9—9 of Fig. 4. Fig. 10 is a bottom view of the center bearing plate.

My invention relates broadly to railway car construction, and specifically to a new and improved form of joint or connection for the center sills and draft sills of a car underframe.

My invention has for its primary object the provision of a form of connection or joint for uniting the center sills and the draft sills of a car underframe which will form a strong and rigid connection wherefore the stresses applied to the draft sills will be transmitted to the center sill, which construction provides for the quick and facile removal of the bolster or other transverse member which commonly intersects the center sills and the draft sills adjacent their point of connection.

The object of my invention also contemplates the provision of a construction wherein the bolster, when in position, acts as a support for the center sill, but may be removed therefrom, whereupon the center sill is supported by the draft sills.

My invention has for further objects the provision of a construction which is strong,

stable, economical, and capable of rapid assembling.

By reference to Fig. 1 of the drawings, it will be understood that 1 represents one of the side sills of the car underframe, 2 the end sill, 4 the body bolster, 5 the center sill, 6 and 6 the draft sills.

By reference to Fig. 2, it will be seen that the draft sills 6 terminate just short of the bolster 4, and that the center sill 5 is formed with a shoulder portion 5^a which abuts the side of the bolster, and an overhanging portion or extension 5^b which projects over and rests upon the top of the bolster. The connection of the center sill with the draft sills is accomplished by means of a pair of connector plates 7, one formed as a left and the other formed as a right. As best shown in Figs. 5 and 6, these connector plates are formed with an aperture or inset 8 extending upwardly from their bottom sides at about their middle portion, which apertures provide passageways for the bolster 4. The sides of these apertures are substantially vertical so as to permit the bolster's being introduced or removed from below without removing the connector plates. Each of these connector plates is formed with an inner vertical web portion 9, which is adapted to abut against the vertical web of the center sill, and an outer vertical web 10 which is adapted to abut against the inner vertical face of one of the draft sills.

The inner and outer webs 9 and 10 are connected by a top flange 11 and a medial flange 12, which flanges are connected by a short vertical flange 14 alined with the inner web 9 and forming substantially a continuation thereof. As illustrated in Figs. 9 and 4, the flanges 11 and 12 and the vertical webs 10 and 14 form a quadrilateral housing or filling block extending above the bolster aperture and continuing across the space intermediate the ends of the center and the draft sills. This forms a very strong and very stable connection. The portions of the webs 9 and 10 adjacent the aperture 8 are finished with the transverse webs 15 and 16 respectively. The outer web 10 is also provided with a bottom horizontal flange 17 integral with the transverse flange 16, and the web 9 is provided with a similar horizontal bottom flange 18 connecting with the transverse web 15. The medial flange

12 forms a broad bearing portion which is adapted to rest on top of the bolster. The flanges 18 and 11 are suitably pitched to conform to the channel side contour of the flanges of the center sill. The web 10 is provided with a top flange 19 which is adapted to rest on top of the upper horizontal flange of the draft sill.

In assembling the connection, webs 9 of a pair of the connector plates are placed against the vertical web of the center sill, and riveted through with the rivets 20. The web 10 of each connector plate is then riveted to the abutting draft sill by the rivets 21, and the flanges 19 are similarly riveted to the top flanges of the draft sills. The bolster then having been positioned in the apertures 8, is secured in place by the rivets 22 of the medial flange 12 and the rivets 24 of the transverse flanges 15 and 16. A cross shaped center bearing plate 23 illustrated in Fig. 10, is then placed in position spanning the apertures 8 at the bottom of the connection, and secured in position by the rivets 25 passing through the bottom flanges of the center sill, and the bottom flanges 18 of the connector plates, the rivets 26 set in the flanges 17, and the rivets 27 set in the bottom flanges of the bolster member.

If it is necessary to remove the bolster for the purpose of repair, such may be accomplished without the removal of the connector plates, and without disturbing the connection of the center and draft sills. This is accomplished by cutting off the rivets 22, 24, 25, 26 and 27, removing the center bearing plate 23, and lowering the bolster from the aperture 8.

This form of connection provides a very strong and rigid joint over the point of support of the underframe. The connection is rendered particularly stable by having the center sill supported directly on the bolster by means of the overhanging portion 5, and by having the center sill and draft sills connected across the top of the bolster by the heavy continuous webs 11 and 12. At the same time, the form of connection provides for economical construction by virtue of the fact that commercial rolled forms can be utilized for the center sill and the draft sill.

I am aware that various changes and modifications may be made in the device which may differ in particulars from the form illustrated and described, without departing from the spirit of my invention, or the scope thereof, as indicated in the appended claims.

What I claim is:

1. In an underframe construction, the combination of a center sill having a portion abutting a side of the bolster, and a portion resting above the bolster, a draft sill terminating adjacent the opposite side of

the bolster, and a connector plate embracing the top and sides of the bolster and provided with flanges connecting the draft sill and the center sill.

2. In an underframe construction, a center sill having a portion abutting the side of the transverse member and a portion overhanging the said transverse member and supported thereon, a draft sill terminating adjacent the opposite side of the transverse member, and a connector plate embracing the top and sides of the transverse member and provided with continuous flanges passing above the transverse member and connecting the center and draft sills, and a removable member passing below the transverse member and connected to the connector plate at opposite sides of the transverse member.

3. In an underframe construction, a center sill and a draft sill offset relative to each other on opposite sides of a transverse member, said center sill having a portion overhanging the transverse member, and a connector plate embracing the top and sides of the transverse member and having offset webs attached to the center and draft sills respectively, said offset webs being connected to each other by flanges passing over the transverse member.

4. In an underframe construction, a center sill and a draft sill horizontally offset from each other, a transverse member disposed intermediate said center and draft sills, said sills having vertical web portions, and a connector plate embracing the top and sides of said transverse member and having a portion in the form of a housing with vertical sides and top and bottom sides spanning the interval intermediate the center and draft sills.

5. In an underframe construction, a connector plate provided with a downwardly opening aperture, a transverse member disposed in said aperture and removable downwardly therefrom, a center sill and a draft sill disposed on opposite sides of said transverse member and offset horizontally from each other, said connector plate being provided with vertical and horizontal web portions, forming a filling member spanning the interval of the lateral offset and longitudinal displacement of the ends of the center and draft sills, and means securing said center and draft sills to said connector plates.

6. In a car construction, a pair of draft sills provided with vertical webs, a center sill provided with a vertical web disposed on a line intermediate the webs of the draft sills, a transverse member disposed intermediate the center sill and the draft sills, and connector members formed with webs attached to the vertical webs of the center and draft sills, said connector members hav-

ing flanges passing above the transverse member and connecting the said webs and forming hollow filling members extending intermediate the ends of the center and draft sills.

7. In a car construction, a draft sill and a center sill offset horizontally relative to each other, a bolster disposed adjacent the juxtaposed ends of said sills and removable 10 downwardly therefrom, and a connector plate attached to said sills on either side of said bolster, said connector plate having a portion in the form of hollow filling members extending intermediate the juxtaposed 15 extremities of the draft and the center sills.

8. In an underframe construction, a pair of draft sills having vertical webs, a center sill having a vertical web alined substantially midway between the draft sill webs, 20 a pair of connector plates having outwardly presented webs secured to the webs of the draft sills inwardly presented webs secured to the web of the center sill and flanges connecting said outwardly and inwardly presented webs, said connector plates being provided with downwardly opening apertures, 25 a bolster disposed in said apertures and a center plate spanning said apertures and extending under the extremities of the center 30 and draft sills.

9. In an underframe construction, the combination of a center sill having a ver-

tical web and lateral flanges, draft sills formed with vertical webs, a bolster interposed between the extremities of said draft 35 sills and said center sill and underlying a portion of the center sill, and a connector plate connecting the center sill with the draft sill and embracing the bolster on three sides; said connector plate having laterally 40 directed flanges adapted to engage the lateral flanges of the center sill, and webs adapted for attachment to the vertical webs of the center and the draft sills.

10. In an underframe construction, a bol- 45 ster member, a connector plate provided with an aperture affording a seat for the bolster member and flanges affording bearing surfaces on three sides of the bolster, a center sill having a portion disposed above 50 the bolster and a portion adjacent one side of the bolster, said center sill being connected to said connector plate, and a draft sill terminating adjacent the opposite side of the bolster and secured to the connector 55 plate.

In testimony whereof I hereunto affix my signature in the presence of two witnesses, this seventh day of March, 1914.

PAUL M. BEARD.
